Primary Examiner — Michael A. Pratt*(74) Attorney, Agent, or Firm* — Hamre, Schumann, Mueller & Larson, P.C.(57) **CLAIM**

The ornamental design for a deodorizing apparatus, as shown and described.

DESCRIPTION

1. Deodorizing apparatus

Figure 1.1 is a front view of a deodorizing apparatus.

Figure 1.2 is a rear view thereof.

Figure 1.3 is a top view thereof.

Figure 1.4 is a bottom view thereof.

Figure 1.5 is a left side view thereof.

Figure 1.6 is a right side view thereof.

Figure 1.7 is a first perspective view thereof.

Figure 1.8 is a second perspective view thereof.

Features shown in broken lines are disclaimed and form no part of the claimed design.

1 Claim, 8 Drawing Sheets Perspective
